CLAIM

The ornamental design for a child resistant push button cap for containers, substantially as shown.

DESCRIPTION

FIG. 1 is a top perspective view of a push button child resistant cap for containers showing my new design, the view showing the top and one side thereof;

FIG. 2 is a top plan view thereof;

FIG. 3 is a side elevational view showing the side opposite that seen in FIG. 1;

FIG. 4 is a front elevational view thereof;

FIG. 5 is a rear elevational view thereof; and

FIG. 6 is a bottom plan view thereof.

FIG. 1

FIG. 2

FIG. 3

FIG. 4

FIG. 5

FIG. 6
